UNITED STATES PATENT OFFICE.

PATRICK FRANCIS DUNDON, OF SAN FRANCISCO, CALIFORNIA.

RETORT-DOOR ATTACHMENT.

1,316,943.

Specification of Letters Patent. Patented Sept. 23, 1919.

Application filed April 17, 1918. Serial No. 229,214.

To all whom it may concern:

Be it known that I, PATRICK F. DUNDON, a citizen of the United States, residing at the city and county of San Francisco and 5 State of California, have invented new and useful Improvements in Retort-Door Attachments, of which the following is a specification.

This invention relates to closing and se- 10 curing means for digester, retort, and like doors, having an internal pressure when closed, which pressure must be relieved before the door is fully opened.

The invention is an improvement upon 15 my Patent No. 653,503, issued July 10th, 1900, and provides for an adjustment and a support for the heavy swinging door, when released from the normal closing de- 20 vices, and while they may be partially re- leased to allow the internal pressure to es- cape before the door is fully opened.

Referring to the accompanying drawing:

The figure is a perspective view of the re- 25 tort door.

1 A represents the retort or other chamber to be employed, 2 is a door frame hermeti- cally secured about the retort opening, and 3 is the door.

Doors for retorts and like chambers which 30 are subjected to internal pressure of steam, gas, or other pressure, must be so disposed that they may be firmly and hermetically closed, when under pressure, and must be first partially released to allow the internal 35 pressure to gradually escape, and finally fully released to entirely disclose the in- 40 terior of the chamber and allow its contents to be removed.

I have found that these operations may 45 be most quickly and accurately effected by supporting the door from one side of the door frame 2 by means of bars 4 which pass loosely through housings 5. The housings are fixed to the door and the bars are hinged 50 to the door frame, and at the ends opposite the hinges are devices to draw the door firmly into closed position.

The door 3 has a tight fitting periphery to form a joint with the door frame, and 55 the slotted housings 5 are secured upon the exterior of the door. Through these hous-

ings the bars 4 pass and are hinged at one end to the door frame, as shown at 6. The bars may be swung about the hinges, carrying with them the door from an open to a 55 closed position, and when closed they are drawn tight by eccentrics 7 and actuating levers 8 which act to press the edges of the door against the door frame. Hook-shaped latches 9 are hinged at opposite sides of the 60 door frame and these latches engage coacting latches on the door. When the locking means are disengaged the door hangs loosely within the housings and may be forced open by the internal pressure until checked by 65 the latches 9, and this allows the interior pressure medium to escape previous to a full opening of the door. When the door is thus released, its weight tends to cause it to sag, and this is resisted by means of a 70 bar 10 which is hinged parallel with the bars 4 and with its pintle in line with those of the bars.

The outer end of the bar 10 passes through a lug 11, fixed to the face of the door, and 75 the end of the bar is screw-threaded to receive a nut 12 which may be turned so that this bar will prevent the door from sagging during its operation. In order to insure the door remaining in its proper position, if re- 80 leased from its hinged supports or by sag- 85 ging, I have shown two fixed bracket lugs 13 projecting from the door frame just be- 90 low the bottom of the door, which may thus rest upon and be supported by these brackets.

By this construction the door is free to move within certain limits in any direction, so that at the instant of closing it will be forced into accurate bearing against all por- 90 tions of its seat, and, when released, will move away from its seat until checked by the latches 9, as before described.

Having thus described my invention, what I claim and desire to secure by Letters 95 Patent is—

In a retort or digester of the character described, an opening in the front, a door therefor having housings fixed thereto with horizontally slotted channels, bars loosely 100 slidable in said channels having hinges at one end about which the bars and door are

turnable, a supplemental bar having one end hinged in line above the main hinges, a lug upon the upper part of the door with a hole through which said bar is slideable, a nut movable upon the threaded end of the bar, and a bracket projecting from the front below the door.

In testimony whereof I have hereunto set my hand in the presence of two subscribing witnesses.

PATRICK FRANCIS DUNDON.
